UNITED STATES PATENT OFFICE.

EDWIN W. SEEGER, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR CONTROLLER.

Application filed November 30, 1925. Serial No. 72,073.

This invention relates to motor controllers, and although not limited thereto the invention is particularly adapted to control of printing press motors.

5 An object of the invention is to provide improved and simplified control means of the above character.

Another object is to provide novel interlocking connections between the various control instrumentalities for accomplishment of the results hereinafter enumerated.

Another and more specific object is to provide a push-button operated controller for effecting forward or reverse operation of the 15 motor, including accelerated operation of the motor, with alternative means for effecting slow speed operation thereof.

Other objects and advantages of the invention will hereinafter appear.

20 The accompanying drawing illustrates an embodiment of my invention which will now be described, it being understood that the embodiment illustrated is susceptible of modification without departing from the 25 spirit and scope of my invention as defined in the appended claims.

In the drawing, Figure 1 is a diagrammatic and schematic view of a controller constructed and arranged in accordance with my 30 invention, and

Fig. 2 is an across-the-line diagram of the circuit connections illustrated in Fig. 1.

Referring more particularly to Fig. 1, M indicates a polyphase induction motor having 35 one terminal, T², of the stator permanently connected to line L², the terminals T¹ and T³ thereof being adapted to be connected to lines L¹ and L³, respectively, upon closure of electro-responsive switch F for operation of 40 the motor in a forward direction, or to lines L³ and L¹, respectively, upon closure of electro-responsive switch R for operation of the motor in a reverse direction; the circuits provided by the aforementioned connections being obvious.

45 The secondary of the motor normally includes a plurality of resistances R¹, R², and R³, each connected at one end to the respective terminals of the rotor, as shown diagrammatically at M¹, M², and M³, each of 50 said resistances being connected at the other end to a common point 5, in the usual manner; whereby said resistances are normally included in the secondary circuit for starting of the motor. Associated with said resistances are adjustable contact arms r¹, r², and

r³, respectively; said arms being preferably provided with a common operating member 6 and suitably insulated from each other, whereby the amount of resistance to be included in the secondary circuit for running 60 may be preselected as desired. Commutation of the secondary circuit from starting to running connections is effected by closure of the electro-responsive accelerating switch AR, which results in short-circuiting of the 65 values of resistance indicated at r¹, r², and r³, as determined by the position of the respective contact arms r¹, r², and r³, as will be obvious.

Control of the aforementioned electro-responsive forward, reversing and accelerating switches is effected by means of a plurality of push-button switches A, B, and C, each of said push-button switches having normally open down contacts, whereas switches A and C are also provided with normally closed up contacts. The switch F is provided with normally open auxiliary contacts 7 for a purpose hereinafter described.

The operation of the controller will now be described, with particular reference to the across-the-line diagram of Fig. 2. Thus, the motor may be started in a forward direction by effecting closure of the normally open down contacts of switch B, thereby providing an energizing circuit for the winding of switch F, which circuit may be traced from line L¹, by conductors 8 and 9 through the normally closed up contacts of switch A, by conductors 10 and 11 through the contacts of 90 switch B, thence by conductor 12 through the winding of said switch F, and by conductor 13 to line L³. Upon closure of the main contacts of switch F the terminals T¹ and T³ are respectively connected to lines L¹ and L³, 95 terminal T² being permanently connected to line L², as aforescribed. The motor is thus started with the full value of resistances R¹, R² and R³ in the secondary circuit.

Switch F in closing effects closure of its auxiliary contacts 7, thereby completing a maintaining circuit for switch F, said maintaining circuit extending from line L¹ to conductor 10, as heretofore traced, thence through the up contacts of switch C, by conductor 14 through said auxiliary contacts 7, by conductor 15 through the operating winding of switch AR, by conductors 16 and 12 through the winding of switch F, and by conductor 13 to line L³. As will be apparent, 110

however, the winding of switch AR is short-circuited in a manner to render operating energization thereof dependent upon release of the switch B, thereby providing for manual control of the duration of the starting period. When said maintaining circuit is rendered effective, by opening of switch B as aforescribed, the winding of switch AR is sufficiently energized to effect closure thereof, thereby short-circuiting the values ω^1 and ω^2 of resistance at the right-hand side of contact arms r^1 and r^2 and the value ω^2 of resistance at the left-hand side of contact arm r^2 , thus providing for acceleration of the motor to the speed preselected by adjustment of said contact arms. If necessary or desirable a suitable resistance 17 may be connected across the terminals of the winding of switch AR for proper adjustment of the relative magnetization of switches F and AR to insure proper cooperation of said switches.

Obviously, at any time after establishment of running connections for the motor, the same may be temporarily brought back to slow speed conditions of operation by re-closure of switch B, which results in deenergization and opening of accelerating switch AR,—accelerating connections for the motor being automatically re-established upon opening of switch B, as aforescribed. Stopping of the motor may be effected at any time during operation thereof by depressing the push-button switch A to effect disengagement of the up contacts thereof, thereby interrupting energization of the windings of accelerating switch AR and forward switch F. Push-button switch A is preferably provided with well known means to permit latching thereof in its intermediate position wherein both the up and down contacts thereof are disengaged.

Operation of the motor at slow speed from rest for inching may be effected by closure of the normally open down contacts of switch C, thereby providing an energizing circuit for the winding of switch F which may be traced from line L^1 to conductor 10, thence by conductor 18 through said down contacts, and by conductors 19, 16 and 12 through said winding to line L^3 . Under these conditions the normally closed up contacts of switch C are opened, thus preventing establishment of the aforementioned maintaining circuit for the winding of switch F, and likewise preventing operating energization of the winding of switch AR, so that upon release of switch C the motor is brought to rest. It will likewise be apparent that the motor may be brought to a slow speed condition of operation from full speed operation thereof by depressing the switch C, whereas upon subsequent release of said switch the energizing circuit of the winding of switch F will be interrupted to bring the motor to rest, as aforescribed.

65 Reversing of the motor may be effected

from full speed forward operation thereof by depressing the push-button switch A to its intermediate position to interrupt energization of the windings of switches AR and F as aforescribed, whereupon further depression of push-button switch A to close the down contacts thereof provides an energizing circuit for the winding of reversing switch R. Said circuit may be traced from line L^1 , by conductor 8 through the down contacts of switch A, by conductor 20 through the winding of said reversing switch, and by conductor 21 to line L^3 . Upon closure of switch R line L^1 is connected to the terminal T^3 of the motor whereas line L^3 is connected to the terminal T^1 to effect operation thereof in the reverse direction, as will be obvious.

While I have shown my invention as applied to the control of one type of motor, it will be apparent to those skilled in the art that the same is likewise adapted for control of other types of alternating or direct current motors.

What I claim and desire to secure by Letters Patent is:

1. In a motor controller, the combination with electro-responsive line and accelerating switches, of control means for said switches comprising a push-button switch biased to open position, said push-button switch having a single closed position and adapted when closed to provide an energizing circuit for said line switch, auxiliary contacts on said line switch adapted upon closure of the latter to complete a maintaining circuit therefor, said maintaining circuit being effective only upon release of said push button switch, the operating winding of said accelerating switch being also included in series in said maintaining circuit and adapted upon utilization of the latter to effect operation of said last mentioned switch for commutation of the motor circuit connections, and a normally closed push-button switch adapted upon opening thereof to effect simultaneous deenergization of both of said electro-responsive switches.

2. In a motor controller, the combination with electro-responsive line and accelerating switches, of control means for said switches comprising a push-button switch biased to open position, said push-button having but one closed position and adapted when closed to provide an energizing circuit for said line switch, auxiliary contacts on said line switch adapted upon closure of the latter to complete a maintaining circuit therefor, said maintaining circuit being effective upon release of said push button switch, the operating winding of said accelerating switch being also included in series in said maintaining circuit and adapted upon utilization of the latter to effect operation of said last mentioned switch for commutation of the motor circuit connections, and a push-button switch

having normally closed and normally open contacts and adapted upon closure and opening of said normally open contacts to effect energization and deenergization of said line 5 switch independently of said accelerating switch.

3. In a motor controller, the combination with electro-responsive forward and reversing switches and an electro-responsive accelerating switch, of push-button switches having normally open contacts adapted when closed to provide energizing circuits for said forward and reversing switches selectively independently of said accelerating switch, 10 and another push-button switch having normally open contacts adapted upon closure thereof to provide an energizing circuit for said forward switch, the latter having normally open auxiliary contacts adapted upon 15 closure to complete a maintaining circuit for said forward switch, said maintaining circuit being effective only upon release of said last mentioned push-button switch and including therein the operating winding of 20 said accelerating switch, to thereby provide for accelerating commutation of the motor circuit.

4. In a motor controller, the combination with electro-responsive forward and reversing switches and an electro-responsive accelerating switch, of a push-button switch having normally closed and normally open contacts and adapted upon closure and opening of said normally open contacts to effect energization and deenergization, respectively, of 25 said forward switch independently of said accelerating switch, another push-button switch having normally open contacts adapted upon closure thereof to effect operating 30 energization of said forward switch, the latter having normally open auxiliary contacts adapted upon closure thereof to complete a maintaining circuit for said forward switch, said maintaining circuit including the operating winding of said accelerating switch and the normally closed contacts of said first-mentioned push-button switch and being effective only upon opening 35 of said second-mentioned push-button switch to provide for closure of said accelerating switch, said second-mentioned push-button switch being also adapted upon subsequent closure thereof to effect temporary deenergization of said accelerating switch, and another push-button switch having normally closed and normally open contacts and adapted upon opening of said normally closed contacts to effect interruption of energization 40 of said forward and accelerating switches and also adapted upon closure of said normally open contacts to effect operating energization of said reversing switch.

5. In a controller for printing press motors, the combination with electro-responsive forward and reversing switches and an electro-responsive accelerating switch, of a push-button switch having normally closed and normally open contacts and adapted upon closure and opening of said normally open contacts to effect interruption of energization 45 of said forward and accelerating switches and also adapted upon closure of said normally open contacts to effect operating energization of said reversing switch.

5. In a controller for printing press motors, the combination with electro-responsive forward and reversing switches and an electro-responsive accelerating switch, of a push-button switch having normally closed and normally open contacts and adapted upon closure and opening of said normally open contacts to effect energization and deenergization, respectively, of said forward switch independently of said accelerating switch, another push-button switch having normally open contacts adapted upon closure thereof to complete a maintaining circuit for 50 said forward switch, said maintaining circuit including the operating winding of said accelerating switch and the normally closed contacts of said first-mentioned push-button switch and being effective only upon opening of said second-mentioned push-button switch to provide for closure of said accelerating switch, said second-mentioned push-button switch being also adapted upon subsequent closure thereof to effect temporary deenergization of said accelerating switch, and another push-button switch having normally closed and normally open contacts and adapted upon opening of said normally closed contacts to effect interruption of energization 55 of said forward and accelerating switches and also adapted upon closure of said normally open contacts to effect operating energization of said reversing switch.

In witness whereof, I have hereunto subscribed my name.

EDWIN W. SEEGER.
